FIG. 1.

FIG. 2.

FIG. 4.

FIG. 5.

FIG. 3.

Inventor

GEORGE ARTHUR SCHIEREN

Freelon D. Mock

Attorney

UNITED STATES PATENT OFFICE.

GEORGE ARTHUR SCHIEREN, OF GREAT NECK, NEW YORK.

SAFETY RAZOR.

Application filed February 27, 1924. Serial No. 695,529.

The present invention relates particularly to an index adjusting device for use in connection with safety razors of the Gillette type wherein a flexible and elastic blade is 5 provided with cutting edges that are adjustable toward and from the guard member of the razor. This adjustment of the cutting edges of the blade is accomplished by 10 turning the handle of the razor to the desired position with relation to the head of the razor. The present invention is an improvement upon the invention disclosed and claimed in my prior patent, Reissue No. 16,264, dated February 16, 1926, and has 15 for its object to simplify and improve the construction of the index adjusting device of that patent.

In the accompanying drawing I have 20 illustrated one complete example of a physical embodiment of my invention, wherein the parts are combined and arranged according to the best mode I have thus far devised for the practical application 25 of the principles of my invention. It will be understood however that changes and alterations may be made in the device as shown without departing from the spirit of my invention, and within the scope of my appended claims.

30 In the drawing, Figure 1 is an elevation of a safety razor embodying the invention; Figure 2 is a view at right angles to Figure 1, showing certain parts in section; Figure 3 is a transverse sectional view on line 35 3—3 of Figure 2; Figure 4 is a fragmentary elevation of the top portion of the handle, with certain parts removed; and Figure 5 is a top plan view of the part shown in Figure 4.

40 In the preferred form of the invention as illustrated in the drawings a safety razor of the Gillette type is shown having the rotatable handle 1 and flexible, elastic blade 2 provided with the opposed cutting edges 45 3, 3, the blade being detachable for cleaning or replacement, and adjustable with relation to the guard plate 4 against which said blade is clamped by the clamp plate 5 which has a central screw or threaded bolt 6 that passes through an opening 6' in the guard plate 4, and also has a pair of spaced posts 7 which pass through guide openings 7' in the guard plate. Such parts 50 may be of the usual and well known form.

The invention is embodied in the handle

portion of the razor which will now be described. The handle 1 is recessed axially to provide a central cylindrical cavity 8, the upper or inner end of which thus forms 60 a thin walled tube 9, the upper end 10 of which is preferably slit at 11 and somewhat expanded in diameter at that point for a purpose which will be hereinafter referred to. The tube 9 may be integral with 65 the handle 1 or separate therefrom, and securely fastened thereto.

Within the tube 9 and fitting snugly therein is a bushing 12, the upper or inner end of which is preferably flanged at 13 and 70 centrally recessed with a central threaded opening 14 adapted to receive the central threaded bolt 6 of the clamp plate 5. The bushing 12 is pinned at 15 to the handle 1 so as to be rigid therewith.

75 The tube 9 is surrounded by a rotary sleeve 16 held against axial movement by the flange 13 of bushing 12 and the shoulder 17 on the handle 1. The upper or inner flanged end 18 of the rotary sleeve 16 carries on its outer periphery a graduated series 80 of indicia marks—as 0, 1, 2, 3, 4, 5—which are adapted to successively register with a fixed mark 19 on the guard plate 4, when the sleeve 16 is rotated.

85 It will be apparent, from the foregoing description, that the sleeve 16 is rotatable on the handle 1 between the flange 13 and the shoulder 17, and that said sleeve is frictionally retarded in its rotary movement 90 by its engagement with the slit and the expanded end 10 of the tube 9 extending from the upper or inner end of the handle 1. Said sleeve 16 will, therefore, rotate with the handle 1 when the latter is screwed on 95 to the bolt 6, but may be rotatably adjusted independently of the handle, during use of the razor after the manner described in the aforesaid Reissued Patent No. 16, 264.

I claim:

1. In a razor of the Gillette type having a guard, a clamp plate having a threaded bolt, a handle adapted to cooperate with said guard and provided with a threaded socket adapted to receive said bolt, said handle having at one end a thin walled tube which is slit and expanded, a rotatably adjustable sleeve swivelled on said tube and frictionally engaging the latter, and cooperating index marks and an index on said sleeve and a fixed part of the razor.
2. In a razor of the Gillette type having

a guard, a clamp plate having a threaded bolt, a handle having a thin walled tube at one end, said tube being slit and expanded, a bushing located in said tube, said bushing having a flanged end and a central threaded opening adapted to receive the threaded bolt of said clamp plate, a rotat-

ably adjustable sleeve swivelled on and in frictional engagement with said tube and retained thereon by the flanged end of said bushing, and cooperating index marks and an index on said sleeve and a fixed part of the razor.

GEORGE ARTHUR SCHIEREN.
